(57) **CLAIM**

The ornamental design for a flexible printed circuit board, as shown and described.

DESCRIPTION

FIG. 1 is a perspective view of a flexible printed circuit board showing our

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged portion view taken from encircled portion labeled, "FIG. 8," in FIG. 2; and,

FIG. 9 is a perspective view thereof, shown in a folded configuration.

The even dashed broken lines illustrate portions of the flexible printed circuit board that forms no part of the claimed design. The dashed-dot lines shown in FIGS. 2 and 8 illustrate the boundary of the enlarged portion view in FIG. 8.
